UNITED STATES PATENT OFFICE.

JAMES G. DUNGAN, OF LOS ANGELES, CALIFORNIA.

HANDLE-FASTENING WEDGE.

1,190,239.

Specification of Letters Patent. Patented July 4, 1916.

Application filed November 25, 1914. Serial No. 873,871.

To all whom it may concern:

Be it known that I, JAMES G. DUNGAN, a citizen of the United States, and a resident of Los Angeles, in the county of Los Angeles and State of California, have invented certain new and useful Improvements in Handle-Fastening Wedges; and I do hereby declare that the following is a full, clear, and exact description thereof, reference being had to the accompanying drawings, and to the letters of reference marked thereon, which form a part of this specification.

This invention relates to a wedge more particularly adapted for use in the attachment of the head of a hammer, hatchet or like tool to the handle, usually made of wood, and rigidly secured in an eye or aperture formed in the head.

It is customary in the attachment of the head of a hammer or hatchet to the handle to use a wooden or metal wedge which is driven in to a split opening in the end of the handle in such manner as to expand the end of the handle in the eye or aperture in the head so as to prevent the head from flying off the handle. Wedges of the kind heretofore produced are objectionable for the reason that while they accomplish the intended function at the time they are applied and for some time thereafter, they ultimately become loose and fail to accomplish the function for which they are intended, and even if hammered home a second time after they have become loose, the frictional engagement of the wedge in its seat after the wedge has once been loosened therefrom is so inefficient that once it has become loose such a wedge can never thereafter be tightened sufficiently to be of much value in holding the head on the handle.

The various advantages of my invention will appear more fully as I proceed with my specification.

In the drawings: Figure 1 is a view representing a side elevation of a hammer in which the head is secured to the handle by means of my improved wedge. Fig. 2 is a view representing an end elevation of the head of the said hammer. Fig. 3 is a view representing on an enlarged scale a section through the hammer and handle in a plane indicated by the line 3-3 of Fig. 2. Fig. 4 is a view representing a transverse section through Fig. 3 in a plane indicated by the line 4-4 of Fig. 3. Figs. 5 and 6 rep-

resent detail perspective views of the parts of my improved wedge. Fig. 7 is a view representing a detail sectional view of a part of the improved wedge showing one of the elements thereof in a slightly modified form.

As illustrated herein I have shown my invention as applied to a hammer but as will be manifest it may be used in connection with any tool in which the handle is secured in an eye in the head.

Referring now to that embodiment of my invention illustrated in the drawings, 10 indicates the head of the hammer and 11, 70 the handle.

12 indicates the eye or aperture in the head in which the handle is secured in a familiar manner.

13 indicates as a whole my improved 75 wedge.

The wedge is made in two parts and comprises a member 14 fixed to the handle and a member 15 which is more particularly intended to produce the wedge action and which is movable with reference to the member 14. The improved wedge is made of metal and the two members 14 and 15 are provided with interacting corrugations or teeth indicated respectively at 14^a-15^a 85 which are adapted by their engagement to prevent movement in a longitudinal direction of the movable wedge member 15 with respect to the fixed wedge member 14. The wedge as a whole is adapted to be engaged with a space left in the eye of the head of the tool by cutting away a part of the handle at one edge as clearly illustrated in Figs. 2 and 3. In order to leave the said space the handle is cut away so as to leave a flat surface 16 and the fixed member 14 of the wedge is rigidly attached against the said surface 16 of the handle. The movable members 15 of the wedge is adapted to be driven into the space in the head left between the fixed member 14 of the wedge and the adjacent surface defining the eye of the tool as indicated in Fig. 3. In the use of the device of attachment of the head of a tool to its handle the said movable member 15 is driven into the space to be occupied by it until the corrugations 15^a on its inner face are engaged with the corrugations 14^a on the outer face of the fixed member of the wedge. In this operation the teeth of the movable member spring by the teeth of the fixed member of the wedge from one engag-

ing position to a further advanced position, the elasticity of the metal of the movable wedge member permitting this action.

The fixed member 14 is fixed to the handle in any convenient manner as by a prong 18. This prong may be separate from or, as is preferable, an integral part of the fixed member of the wedge. As shown the said prong is made by cutting a strip of metal 10 from the fixed wedge member itself and bending the same away from the plane of the said wedge member, as clearly indicated in Figs. 3 and 5. The part cut away to form the said prong is preferably bent so that 15 when applied to the handle of a hammer it will be inclined toward the end of said handle that is toward the head of the hammer. In applying the wedge to attach the head of a tool to its handle, the fixed member 14 is first 20 rigidly attached to the flat surface 16 at the end of the handle by driving the prong 18 into said handle. The end of the handle is then slipped into the eye 12 of the head in the usual manner and the movable member 15 of 25 the wedge driven into the space in the eye of the head between the fixed member 14 of the wedge and the adjacent wall of the eye. Said movable member is driven in until the coacting corrugations 14^a—15^a of the said 30 parts of the wedge are brought into engagement and until the head is properly wedged upon the handle.

Should the handle become loose in the head owing to the contraction of the handle 35 under temperature or moisture conditions of the atmosphere, the wedge may be tightened either by driving the movable member of the wedge farther into the eye or by striking the hand end of the handle in such manner as to 40 move the fixed part of the wedge member with reference to the movable member thereof. In this operation the corrugations will be engaged together in a new relation and the head will become as rigid on the handle 45 as in the first place.

In order to supplement the action of the wedge I prefer to provide a short knife wedge 19 adapted to extend transversely of the eye in the handle and engage a suitable 50 V notch or split 20 in the end of the handle. This supplemental part acts in the same way as the usual wooden wedge and supplements the action of the movable member 15 of my improved wedge.

55 In order to facilitate the removing of the head from the handle in case the handle is damaged and it is desired to replace the same with a new handle, I may use a modi-

fication of the device as shown in Fig. 7, in which the movable member of the wedge is 60 provided with a hinged part 21 which has the corrugations 21^a adapted to coact with the corrugations 14^a on the fixed member of the wedge. The said hinged part is connected with the other part of the movable 65 member in such manner that it may be swung outwardly on its hinge as indicated by dotted lines to disengage the coacting teeth of the two members of the wedge, but the hinge is made stiff enough so that the 70 two parts will coact as above described and the hinged part may only be forced from its engagement with the fixed member of the wedge by the use of force, as for example, by inserting a screw driver or other 75 tool.

I claim as my invention:

1. A wedge device of the kind described comprising two members, one of said members having an integral prong adapted to be entered into the handle adjacent its end to affix said member to said handle, and the other of said members being adapted to be driven in the manner of a wedge into the eye of the head of the tool adjacent the other member and in engagement therewith, said member having a supplemental wedge at its top end adapted to enter the handle and each of said members being provided with interacting interlocking teeth at their bottom ends.

2. A wedge device of the kind described comprising two members, one of said members having an integral prong adapted to be entered into the handle adjacent its end to affix said member to said handle and the other of said members being adapted to be driven in the manner of a wedge into the eye of the head of the tool adjacent the other member and in engagement therewith, said member having a supplemental wedge at its top end adapted to enter into the handle, each of said members being provided with interacting interlocking teeth at their bottom ends, the last mentioned member including a hinged part upon which is formed the teeth of said member.

In testimony, that I, claim the foregoing as my invention I affix my signature in the presence of two witnesses, this 20th day of November A. D. 1914.

JAMES G. DUNGAN.
